DESIGN FOR A TEXTILE FABRIC OR SIMILAR ARTICLE

Ludolf Portong, New York, N. Y.

Application October 24, 1936, Serial No. 65,470

Term of patent 3½ years

To all whom it may concern:

Be it known that I, Ludolf Portong, a citizen of the United States of America, residing in Manhattan, county of New York, and State of New York, have invented a new, original, and ornamental Design for a Textile Fabric or Similar Article, of which the following is a specification, reference being had to the accompanying drawing, forming part thereof, wherein,

The figure is a plan view of a piece of textile fabric or similar article, showing my new design.

The design consists of a combination of anchors and sails upon a contrasting striped background, arranged in alternate staggered rows, as shown.

I claim:

The ornamental design for a textile fabric or similar article, substantially as shown, and described.

LUDOLF PORTONG.
